US00D588925S

(12) **United States Design Patent**
DeMarco

(10) **Patent No.:** **US D588,925 S**
(45) **Date of Patent:** **** Mar. 24, 2009**

(54) **CONTAINER**(75) Inventor: **Jenny DeMarco**, Addison, TX (US)(73) Assignee: **Mary Kay Inc.**, Dallas, TX (US)(**) Term: **14 Years**(21) Appl. No.: **29/306,117**(22) Filed: **Apr. 2, 2008**(51) LOC (9) Cl. .... **09-01**(52) U.S. Cl. .... **D9/558; D7/602; D7/316**(58) **Field of Classification Search** **D9/50, D9/682, 686, 688-692, 500-575; D28/76, D28/78, 82; D7/509, 602; 215/379, 381-382; 220/660, 662, 669, 675**

See application file for complete search history.

U.S. Appl. No. 29/306,116, filed Apr. 2, 2008, DeMarco.

Primary Examiner—Charles A Rademaker*Assistant Examiner*—Dana L Sipos(74) *Attorney, Agent, or Firm*—Fulbright & Jaworski L.L.P.(57) **CLAIM**

The ornamental design for a container, as shown and described.

DESCRIPTION

FIG. 1 is a top, front, right side perspective view of a container showing my new design;

FIG. 2 is a front elevation view thereof, the rear elevation view being identical;

FIG. 3 is a left side elevation view thereof, the right side elevation view being identical; and,

FIG. 4 is a top plan view thereof.
